UNITED STATES PATENT OFFICE.

ROSCOE BERRINGER, OF DETROIT, MICHIGAN, ASSIGNOR TO GENERAL MOTORS CORPORATION, OF DETROIT, MICHIGAN, A CORPORATION OF DELAWARE.

CONVERTIBLE BODY.

Application filed November 24, 1924. Serial No. 751,903.

This invention relates to convertible automobile bodies of the type in which the space below the top is closed, when desired, by glass panels. An object of the invention is to provide a body of this character in which the panels mounted on the tops of the doors are readily accessible and are easily manipulated when being raised and lowered, and at the same time are fully protected when not in use.

In the arrangement shown in the drawings, each door is in two sections, the outside section being arranged to swing outward independently of the inside section to permit the panel to be moved into a storage space between them when not in use. Preferably the panel is hinged at the top edge of one of the sections and the outer section is hinged at the bottom edge of the inner section. Various features of the invention relate to an improved latching device for securing the sections together and to a construction of the door permitting the use of a panel the full width of its door, together with a novel lock for the door arranged to be operated by a handle on the swinging outer section which is automatically brought into operative position by closing the sections together.

These various features of novelty, and other desirable details of construction, will be apparent from the following description of one illustrative embodiment shown in the accompanying drawings, in which:

Figure 1 is a side elevation of the described convertible body when closed;

Figure 2 is a similar view of the body when it is open, i. e. when the panels are lowered;

Figure 3 is an inside elevation of one of the doors, partly broken away to show some of the interior mechanism;

Figure 4 is a top plan view of the door when the panel is down;

Figure 5 is a vertical section on the line 5—5 of Figure 4 and showing the outer section of the door in side elevation;

Figure 6 is a vertical section on the line 6—6 of Figure 4 and showing the inside section of the door in outside elevation;

Figure 7 is a vertical section on the line 7—7 of Figure 3, but on a larger scale, showing part of the operating mechanism for the lock; and

Figure 8 is a vertical section through the door and its panel illustrating the manner of swinging the panel from operative to inoperative position.

In the arrangement selected for illustration the invention is shown embodied in an automobile body 20 having a top 22, shown as a permanent top. The space between the body and top rearwardly of the doors may be closed, when desired, by a glass panel 24 of any desired construction.

According to the present invention each door carries a panel which may be swung up into a position above the door to close the space between the door and the top. The doors 26 and 28 are shown hinged, respectively at their front and rear edges and having flanges projecting toward each other at their adjacent meeting edges to form rabbeted portions overlapping and concealing a door post which is common to the two doors. Each door is in two sections, the inner section 30 being provided with the hinges 32 connecting the door to the body, and the outer section 34 being hinged to the inner section along its bottom edge as shown in Figure 8. Outward movement of the section 34 is limited by one or more flexible straps 36 which, when the sections are closed, and the glass panel 38 is not in use, embrace the lower edge of the panel to cushion it against rattling inside of the door.

The panel 38, shown as a sheet of glass mounted in a metal frame 40, is hinged at the top of one of the sections, preferably the inner section 30. As is illustrated in Figure 8, when section 34 is swung out as far as it will go, the panel 38 may either be swung into its upper operative position or into its lower position in which it is housed between the two sections of the door. The panel is the full width of the door, the two sections of the door being arranged to form intermediate storage space which is open at both ends of the door, to permit the use of this width of panel. The lower position of the panel, and the manner in which it extends flush with both edges of the door, is illustrated in Figure 6, which figure also shows the hinges 42 for the panel. These hinges are long enough to project through openings 44 in the top edge of the outer section 34 when the panel is in its upper position.

When the sections are closed together they are fastened together by spring pressed bolts 46 carried by the inner section and projecting into sockets in lugs 48 carried by the outer section. These spring pressed bolts are withdrawn, to permit the sections to be separated,

by rocking a shaft 50 by means of a handle 52 projecting through an opening in the inner section 30 to a position in which it is accessible from inside of the car.

5 The lock 54 of the door is mounted on the inner section 30, the bolt 56 being operated by an upwardly extending handle 58 accessible from the inside of the car. As is best shown in Figure 7 the handle 58 is provided with a 10 horizontally extending lug 60 which, when the sections are closed, is in the path of an arm 62 operated by handle 64 on the outside of the door. Thus the handle 64 swings outwardly with the outer section 34 and is brought back 15 into operative relation with respect to the lock when the section is closed again.

While one illustrative embodiment has been described in detail, it is not my intention to limit the scope of the invention to that 20 particular embodiment, or otherwise than by the terms of the appended claims.

I claim:

1. A vehicle body including an outwardly-opening door, the door having its outside 25 formed as a separate part swinging outwardly independently of the remaining part of the door, and a panel housed between the parts of the door when not in use and movable to a position above the door when the two parts are 30 separated by swinging the outside part of the door open.

2. A vehicle body including an outwardly-opening hinged door, the door having its outside formed as a separate part hinged at its 35 lower edge and swinging outwardly independently of the remaining part of the door, and a panel hinged to the top edge of one of the parts of the door and housed between the parts of the door when not in use and movable 40 to a position above the door when the two parts are separated by swinging the outside part of the door open.

3. A vehicle door comprising two parts 45 hinged together to inclose a panel, one part having a lock, and the other part having an operating device for the lock which is brought into operative position with respect to the lock by closing the two parts of the door together.

50 4. A vehicle door having a panel hinged thereto for movement into an operative position above the door, the door being formed to inclose the panel when not in use, and the door and the panel being equal in width and 55 arranged so that their lateral edges align when the panel is in operative position.

5. A vehicle door comprising two sections 60 hinged together at their bottom edges, and arranged to provide a central space open at both ends of the door, and a panel hinged at the top edge of one section, the panel being the same width as the door and being flush with the ends of the door when housed between said sections.

6. A vehicle door comprising two sections 65 hinged together along one edge, latch members at the free edges of the sections for detachably holding the sections closed, a rock-shaft between said sections for operating the latch members, and a member on the outside 70 of one of said sections for rocking the shaft.

7. A vehicle door comprising two sections hinged together at their bottom edges, a panel 75 hinged at the top edge of one section and movable above the door or between said sections when not in use, and a flexible strap limiting separation of said sections and embracing the free edge of the panel when the sections are together with the panel between them.

8. A vehicle door comprising two sections 80 hinged together to afford a storage compartment between them, a flexible strap limiting separation of said sections, a panel for positioning at the top of said door or for storage between said sections, said strap being adapted to embrace an edge of said panel and restrain its movement.

9. In an automobile, the combination of a body and a door for the body comprising an inner section pivoted to the body and an outer 90 section pivoted to the inner section, said sections being arranged to provide a storage space between them.

10. The combination as defined in claim 9, and a panel adapted to be positioned upon the upper portion of the door and having a width equal to the width of the door, said panel being received within the storage space when not in use.

11. A vehicle door comprising two parts 100 adapted to be secured together to form a pocket and to be separated to afford access to the pocket, a latch for the door carried by one of said parts and latch operating means carried by the other part and detachably associated with said latch to permit ready separation of said parts.

12. A vehicle door comprising two parts adapted to be secured together to form a pocket and to be separated to afford access to 110 the pocket, a latch for the door carried by one of said parts, latch operating means carried by each of said parts, one of said latch operating means being detachable from said latch to permit separation of said parts.

115 13. A vehicle door comprising two parts adapted to be secured together to form a pocket and to be separated to afford access to the pocket, a latch, a latch operating means carried by one of said parts, and an operating 120 means carried by the other part and arranged to actuate said latch operating means, the operating means and the latch operating means being readily detachable to permit separation of said parts.

125 In testimony whereof I affix my signature.

ROSCOE BERNINGER.
